ELECTRIC HEATING APPARATUS

Charles H. Hodgkins, Fairfield, Conn., assignor to
 Westinghouse Electric & Manufacturing Company, East Pittsburgh, Pa., a corporation of Pennsylvania

Application November 29, 1939, Serial No. 306,656

5 Claims. (Cl. 219—20)

My invention relates in general to electric heating apparatus, and more particularly to apparatus of this type having a control circuit adapted to provide a plurality of different degrees of heat from the heating elements employed.

This type of electric heating apparatus finds one application in heaters for cooking purposes, such as ranges, ovens and the like, and various embodiments of my novel apparatus will be disclosed particularly for applications of this type, although it should be understood that my invention is applicable to any desired application of electric heating apparatus.

One object of my invention is to provide new and improved electric heating apparatus of the above-mentioned type.

Another object of my invention is to provide a novel arrangement of electrical heating apparatus wherein a single control member is adapted to provide a plurality of different degrees of heat from said apparatus.

Another object of my invention is to provide a novel arrangement of electrical heating apparatus wherein a single control member is adapted to connect the heating elements to a plurality of different voltage values in a plurality of different relations thereto.

A further object of my invention is to provide simplified apparatus of this type which is efficient in operation.

A still further object of my invention is to provide a single control for heating apparatus capable of connecting the apparatus in different circuits to obtain different degrees of heat from the apparatus, while confining the arcs formed by interruption of said circuits to a predetermined arcing zone.

These and other objects of my invention will become more apparent upon consideration of the following detailed specification of preferred embodiments of my invention, and taken in connection with the attached drawings, in which:

Figure 1 is a perspective view of a control switch for controlling electrical heating apparatus.

Fig. 2 is a plan view of the switch shown in Fig. 1 with the handle and cover plate removed, and a portion of the arcing shield broken away;

Fig. 3 is a bottom plan view of the switch shown in Fig. 1;

Fig. 4 is a plan view of the interior of the switch similar to Fig. 2, but with the contact operating member and its indexing means removed;

Fig. 5 is a central longitudinal cross-sectional view of the switch shown in Figs. 1 to 4;

Fig. 6 is a diagrammatic view illustrating one arrangement of electric heaters in accordance with my invention and utilizing the control switch shown in Figs. 1 to 5, with the bridging contact shown at the central vertical axis of the switch as viewed in Fig. 4;

Fig. 7 is a view similar to Fig. 6 but illustrating another embodiment of my invention; and

Fig. 8 is a view similar to Figs. 6 and 7 but showing still another embodiment of my invention; and,

Fig. 9 is a diagrammatic view illustrating another arrangement of heating apparatus.

The switch per se disclosed herein is particularly claimed in my copending application, Serial No. 306,655, filed November 29, 1939, and assigned to the Bryant Electric Company.

The switch shown in Figs. 1 to 5, generally is of the multi-position type and two methods of making contact are employed; (1) in which movable, normally spring closed contacts are operated by cams to cause these contacts to engage or disengage from stationary contacts, and (2) in which pairs of stationary segmental contacts are bridged by a sliding shoe carried by the cam which operates the spring contacts.

The connection relation of this switch with respect to the circuit which it controls is such that the circuit is always made or interrupted by the cam operated spring contacts engaging with or separating from their cooperating stationary contacts. Therefore, arcing occurs at these contacts only.

The relation of the segmental contacts and the sliding shoe to the cams which operate the spring contacts is such that there is a definite timing in the functioning of all contacts. When switching from one position to another, the sequence is as follows: The spring contacts are first opened by the cam. The sliding shoe moves from one set of segmental contacts to another set and the spring contacts are then closed, thereby completing the circuit. The sliding shoe and segmental contacts can, therefore, be considered as set-up contacts or circuit selecting contacts, and no arcing can occur at this point.

Referring to the drawings, I have illustrated a switch which is mounted in an insulating casing 2, which may be of any desired heat resistant insulating material such, for example, as a moulded insulating material such as Bakelite. The insulating casing 2 includes a bottom wall 4, opposed side walls 6, and end walls 8. The bottom wall

4 of the casing is provided with a central aperture 10 for receiving a reduced end portion 12 of the switch operating shaft. Concentric with the aperture 10 in the bottom wall of the casing, there is provided concentric annular grooves 14 and 16. In the outer groove 14 there is mounted spaced arcuate contact segments 18, 20, and 22 maintained in spaced relation by the arcuate insulating segments 28. These segments may be maintained in the groove 14 in any desired manner, preferably by friction. The contact segments may be of any desired conducting material such, for example, as copper or the like. The inner groove 16 is likewise provided with spaced arcuate contact segments 24 and 26 maintained in spaced relation by the arcuate insulating segments 28. The segments are preferably slightly raised above the adjacent surface of the bottom wall 4 of the switch casing as shown in Fig. 5.

The operating shaft is provided with an enlarged cylindrical portion 30 adjacent the reduced portion 12, and forming a shoulder 32 which is adapted to abut against the bottom wall of the switch casing to limit movement of the operating shaft into the switch casing. The operating shaft is also provided with an intermediate hexagonal portion 34, forming a shoulder 36 at its juncture with the portion 30, and an outer reduced portion 38 forming a shoulder 40 at its juncture with the hexagonal portion 34. The outer end of the operating shaft is reduced as at 42 to receive an operating handle 148.

A contact operating member 44 of any desired insulating material such, for example, as a moulded insulating material such as Bakelite, is slipped over the reduced end of the operating shaft 12 until the shoulder provided in the aperture through the operating member 44, engages the shoulder 36 on the operating shaft. The enlarged portion of the aperture through the operating member 44 is made hexagonal in shape to correspond with the hexagonal portion 34 of the operating shaft, to lock the operating member 44 for movement with the operating shaft. The contact operating member 44 is formed on its lower side with integral annular concentric projections 46 positioned to be received in spaced annular depressions 48 provided in the bottom wall 4 of the switch casing. These projections 46 are provided between the sets of contact segments, and between the operating shaft and the inner set of contact segments, respectively, to reduce the creepage distance between these parts. The contact operating member 44 is provided with an opening 50 which opens toward the bottom wall 4 of the switch casing, and has an enlarged open-end portion 52 in which is received the contact segment bridging contact 54, which is elongated in shape and has an outwardly extending integral projecting portion 56, extending into the inner portion of the aperture 50 and telescoping into one end of a coil compression spring 58, which bears against the bridging contact 54 at one end thereof, and engages the closed end of the aperture 50 at its other end. The coil spring 58 acts to continuously urge the bridging contact 54 into engagement with the contact segments.

Mounted in the two corners of the switch casing at one end thereof, are fixed contact supports 60 and 74 carrying the contact portions 62 and 76, respectively. The contact supports may be made of any suitable conducting material such as brass, copper, or the like, but the contacting portions thereof are preferably made of a metal capable of withstanding repeated arcing, such

as silver or a silver alloy. Cooperating with the contacting portions 62 and 76 are the resilient contact carrying arms 64 and 78, respectively, secured in the opposite corners of the switch casing, on conducting supporting members 66 and 80, respectively. The resilient contact carrying arms carry at their free ends contacting portions 70 and 84 for cooperation with the contact portions 62 and 76, respectively, and are formed of a like material. The resilient contact carrying arms 64 and 78 are stressed so as to normally engage their contacting portions with the fixed contacts 62 and 76. Each of the resilient contact carrying arms 64 and 78 is provided at substantially its mid-portion with a struck-out part 72 and 86, respectively.

As viewed in Figs. 2 and 4, the struck-out portion 86 of the resilient contact carrying arm 78 is struck out of the upper edge of this contact carrying arm, whereas, the struck-out portion 72 of the other arm 64 is struck out adjacent the lower edge of that contact carrying arm, all for a purpose hereinafter to be described. The contact carrying arms 64 and 78 are secured to the supports 66 and 80, respectively, by any suitable means such, for example, as by rivets 68 and 82, respectively. Also secured to the support 66 by the rivets 68 is a fixed contact strip 88, having an angularly extending contact portion 90. A substantially U-shaped resilient conducting member 92 integral with a supporting member 94 secured in the switch casing in any desired manner, has one leg 96 thereof extended for cooperation with the fixed contact 90. An intermediate portion of the leg 96 is struck out as at 98 for a purpose to be hereinafter described.

The contact operating member 44 is provided with peripheral cam surfaces, as shown especially in Fig. 2. These cam surfaces are provided for cooperation with the struck-out portions 72, 86 and 98 of the three resilient contact bearing arms. As shown in Fig. 2, the periphery of the contact operating member is provided with outer indented portions 100, 101 and 102 for cooperation only with the outer struck-out portion 86 of the resilient contact carrying arm 78. These indented portions 100, 101 and 102 are provided only in the outer portion of the peripheral surface of the contact operating member 44 as is apparent from Fig. 2. The contact operating member 44 is also provided with indentations 104 and 106 which extend throughout the width of the periphery of the contact operating member 44, so as to operate, or engage with both of the indented portions 86 and 72 of the resilient contact carrying arms. The contact operating member 44 is further provided with an outwardly offset protuberance 108 for engagement only with the resilient contact arm 96.

As shown in Figs. 2 and 4, I have provided an insulating barrier 164 integral with the switch casing and positioned between the fixed contacts 62 and 76. The insulating barrier 164 is provided with arcuate extensions 166 to substantially isolate the contacts 62 and 76 from the contact segments. A cover 150 is suitably secured to the open side of the switch casing, for example, as by the machine screws 151. Secured between the cover and the casing is an arcing shield 152 of insulating material such, for example, as fiber or the like, which, together with the switch casing and the insulating barrier 164, 166, completes the substantial enclosure or segregation of the contacts 62 and 76 from each other and from the con-

tact operating member, and contact segments provided in the bottom of the switch casing.

For indexing the contact operating member in the desired operating positions, I have provided resilient rod elements 154 and 156 on opposite sides of the hexagonal portion 34 of the operating shaft with corresponding ends of the resilient rods received in notches 158 provided in one side wall of the switch casing, and with the opposite ends of the resilient rods received in notches 160 provided in the opposite side wall of the insulating casing, which latter notches are elongated to receive the coil compression spring 162 engaging between the resilient rods 154 and 156, respectively, and the outer ends of the notches 160. The 15 springs 162 act to maintain the resilient rods 154 and 156 in engagement with the opposed flat sides of the hexagonal portion 34 of the switch operating shaft. Thus, in turning the shaft, it is necessary to slightly separate the resilient rods 154 and 156 by a cam action of the hexagonal portion 34 of the switch operating shaft, until another set of opposite flat surfaces on the shaft are brought into flush engagement with the resilient rods. This will clearly indicate to the manipulator when an operating position of the switch has been reached, and the resilient rods 154 and 156 under the influence of the springs 162 will tend to maintain the switch in its operative positions. A handle 148 is frictionally fit on the outer end of the switch operating shaft and is provided with suitable indicia, which will be hereinafter referred to.

The various switch connections which I have provided in this embodiment of my invention will have use primarily in the circuit shown in Fig. 6. The switch proper is provided with a terminal 110 which has portions extending through the casing bottom wall and connected with the contact segment 18 and the conducting support 66, respectively, which in turn connects this terminal with the resilient contact arm 64 and its contact portion 70 and with the fixed contact 88 and its contacting portion 90. The terminal 112 of the switch is electrically connected through the bottom wall of the switch casing with the support 80, thus connecting this terminal with the resilient contact arm 78 and its contacting portion 84. A terminal 114 is provided on the back of the switch and, as shown in Fig. 5, includes an inner angular portion 116 extending through the bottom wall of the casing and connected with one leg of the U-shaped resilient contact 92 shown in the upper end of the switch casing in Fig. 4. The terminal 118, also provided on the back of the switch casing on one side thereof, is provided with an integral extension 120, extending through the bottom wall of the switch casing, as shown in Fig. 5, which is in turn, integral with the contact segment 24. The switch terminal 122 at the back of the switch casing is connected through the bottom wall of the casing to the fixed contact support 74, and has an extension 123 for connection with a portion extending through the bottom wall of the switch casing for connection with the contact segment 22. The switch terminal 126 also mounted on the back of the switch casing is connected to the fixed contact support 60 through the bottom wall of the casing, and is provided with an extension 127 for connection through the bottom wall of the casing with the contact segment 26. The terminal 124 70 of the switch casing is provided with a connection through the bottom wall of the casing to the contact segment 20. These connections of the switch terminals with the corresponding contacts or contact segments are readily apparent from an in-

spection of Figs. 5 and 6. All the switch terminals are provided with screws 128 for attaching lead wires thereto.

Referring now particularly to Fig. 6 I have 5 illustrated in schematic form, one embodiment of my invention utilizing the switch described above, in a circuit for controlling a heater element composed of two identical resistance sections 138 and 140 and supplied with current from a three 10 wire source of supply giving, for example, 250 volts between the positive and negative conductors of the supply circuit and one-half that value, or 125 volts between either the positive or negative conductors and the grounded neutral conductor. As shown in Fig. 6, the switch terminal 112 is connected by a conductor 130 to the positive conductor of the supply circuit. A conductor 132 connects the neutral conductor of the supply circuit with the switch terminal 124, and 20 a conductor 134 connects the switch terminal 110 with the negative conductor of the supply source. The terminal 114 of the switch is connected to the neutral conductor of the supply circuit through a pilot lamp 136. One end of the resistance heater element 138 is connected by conductor 142 to the switch terminal 122. One end of the resistance heater element 140 is connected by the conductor 146 to the switch terminal 118, and a conductor 144 connects the 25 switch terminal 126 to the other ends of the resistance heater elements 138 and 140.

I have illustrated in Fig. 6 the six positions 30 of the switch used with this particular circuit. This is capable of providing five different degrees of heat from the heating elements 138 and 140. At the extreme right in Fig. 6, I have illustrated the "off" position of the switch wherein all contacts are open and the circuit through the pilot lamp 136 is broken. To the left of this, I have illustrated the first or lowest heat position, labeled the "simmer" position, wherein the circuit through the switch extends from the positive conductor of the supply source through conductor 130, terminal 112, resilient contact arm 78, 35 fixed contact 74, terminal 122, conductor 142, resistance elements 138 and 140, conductor 146, switch terminal 118, contact segment 24, bridging contact 54, contact segment 20, switch terminal 124, and conductor 132 to the neutral conductor of the supply circuit. This provides 125 volts across the two resistance elements 138 and 140 connected in series, thus providing, for example, with a resistance of approximately 62.5 ohms, and assuming unity power factor, substantially 40 125 watts of heating effort. The other four heating positions of my switch are illustrated to the left of the "simmer" position with progressively higher heating effects provided by successive positions of the switch. Thus, in the position marked "low," the heating element 138 alone is subjected to 125 volts, and at the "low medium" position the heating elements in series are connected across 250 volts. In the "medium" position, the heating element 138 alone is connected across 250 volts, and in "high" position, each of the heating elements 138 and 140 is individually connected, or connected in parallel across 250 volts. The voltage and wattage are marked for 45 each of the positions shown in Fig. 6.

The sequence of operation of the contacts of the switch are as follows. The switch, as shown in Figs. 1 to 5 is in the "off" position, corresponding to the "off" position shown in Fig. 6. 50 It will be noted that in this position, referring

particularly to Figs. 2, 4 and 6, the resilient contact arms 64 and 78 are maintained by the contact operating member 44 out of engagement with their cooperating fixed contacts 62 and 76, respectively. Also, the switch operating member 44 is in a position such that the segment bridging member 54 engages only the segment 24. Also, the projection 108 on the contact operating member is in engagement with the struck-out portion 98 on the leg 96 of the U-shaped resilient contact controlling the pilot lamp 136, to maintain the resilient contact out of engagement with its cooperating fixed contact 90. Upon movement of the switching handle from the "off" position in a counterclockwise direction, as viewed in Figs. 1, 2 and 4, to the next or "simmer" position, it is obvious that the resilient contact bearing arms 64 and 78 will remain open until the bridging contact 54 is in a position to bridge the contacts 24 and 20, after which the struck-out portion 86 of the resilient contact carrying arm 78 registers with the indentation 104 provided on the switch operating member 44, to permit the contacts 84 and 76 to close to complete the circuit to the heating element 138. It is thus apparent that the circuit is first set up by the bridging contact 54 and the contact segments, and then the circuit is closed by the arcing contacts 76 and 84.

In moving the switch operating member from the "simmer" position to the next or "low" position, it is obvious that the first thing that takes place is engagement of the struck-out portion 86 of the resilient contact carrying arm 78 with the protuberance below 108 on the contact operating member 44 to open the contacts 76 and 84 prior to disengagement of the bridging contact 54 with the contact segments 20 and 24. The bridging contact 54 then moves from engagement with the contact segments 20 and 24 into engagement with the contact segments 20 and 26, and thereafter, the indentation 106 on the contact operating member 44 registers with the struck-out portion 86 on the resilient contact carrying arm 78, to permit the contacts 76 and 84 to close.

This same sequence of operations of the switch contacts takes place upon movement of the switch to all of its six positions. In other words, the arcing contacts 76 and 84, and 62 and 70 are first opened upon movement of the switch from one position to another before the bridging contact 54 leaves one set of contact segments to engage with another set of contact segments. These arcing contacts remain open until the bridging contact 54 has engaged with the next set of contact segments, whereupon one or both of the arcing contacts may be closed depending upon whether the resistance elements are to be connected between one of the live conductors of the supply circuit and the neutral conductor, or whether they are to be connected between the two live conductors of the supply circuit. It is thus obvious that no arcing can occur at the small contact segments where the circuits through the switch are selected, and that all arcing is done at one or both of the heavy arcing contacts 76, 84 and 62, 70, in especially provided arcing chambers which are substantially insulated from the contact segments and the contact operating member 44.

This type of switching arrangement makes it possible to reduce the number of contacts requiring special arcing metals, and also permits

the provision of special arcing chambers to prevent distress due to flash-over from one arcing contact to another. The small space required by the segmental contacts, and sliding bridging contact, lends itself readily to a device of small dimension and permits great flexibility since a variety of arrangements of segmental contacts may be employed for the control of different circuits.

In Fig. 7 I have shown another schematic form illustrating an arrangement of a switch similar to that shown in Figs. 1 to 6 for controlling a pair of heating elements 159 and 161 of unequal resistance, and having six positions as in Fig. 6 which includes an "off" position and five heating positions. The switch used in this embodiment of my invention is the same as that shown in detail in Figs. 1 to 5 with the exception of a slightly different arrangement of contact segments, and hence like reference numerals are used to designate like parts.

As shown in Fig. 7 the heating elements or resistors 159 and 161 are supplied from a three wire source of electrical energy similar to that described in Fig. 6.

Referring in particular to the "off" position shown in Fig. 7, I have shown a conductor 149 connecting the positive wire of the supply circuit with the switch terminal 153, which in turn is connected with the resilient contact arm 78 of the switch. A conductor 163 also connects the positive conductor of the supply circuit with a terminal 167 of the switch which is connected with the resilient contact arm 96, cooperable with the fixed contact 90, which in turn is connected with the switch terminal 166 for controlling a pilot lamp 136 in series with the conductor 168 connecting the switch terminal 166 with the neutral conductor of the supply circuit. A conductor 170 connects the neutral conductor of the supply circuit with the switch terminal 172, which is connected with the resilient contact arm 64 of the switch. The contact segment 190 is electrically connected by the conductor 165 with the contact arm 64. The resistor 159 which has a greater resistance than the resistor 161, has one end thereof connected by the conductor 174 to the switch terminal 176, which is connected with the inner annular switch contact segment 178. The resistor 161 has one end thereof connected by a conductor 180 with a switch terminal 182, which is connected to the fixed switch contact 60. The other ends of the resistors are connected by a common conductor 157 to the switch terminal 155, which in turn is connected with the fixed switch contact 74. The negative conductor of the supply circuit is connected as by the conductor 184 with the switch terminal 186, which is in turn connected with the switch contact segment 188.

Assuming that the supply circuit is capable of supplying the same voltages as in Fig. 6, that is, for example, 250 volts between the positive and negative conductors and 125 volts between the neutral conductor and either of the other two conductors, and further assuming by way of illustration that the resistor 159 consumes 1400 watts when connected across 250 volts and the resistor 161 consumes 600 watts when connected across 125 volts, the several positions illustrated in Fig. 7 will give the several wattages marked thereon. The switch used in Fig. 7, of course, has a single controller like the switch shown in Figs. 1 to 6 and the positions marked on Fig. 7 will correspond to those provided on the controller in the

same sequence in which they appear in Fig. 7. In the "off" position shown in Fig. 7 it is believed obvious that neither resistor will be supplied with electrical energy and that the circuit for the pilot lamp 136 will also be opened.

In the next position to the left of the "off" position or the position marked "super," the connections are as follows: One circuit extends from the negative conductor of the supply circuit through conductor 184, switch terminal 186, contact segment 188, bridging contact 54, contact segment 178, switch terminal 176, conductor 174, to one end of the resistor 159, to the conductor 157, switch terminal 155, switch contact 14, resilient contact arm 78, switch terminal 153, conductor 149 to the positive conductor of the supply circuit, thus providing for the voltage values given above, 250 volts supplied to the resistor 159. The circuit for the other resistor 161 extends from the conductor 157 and the positive conductor of the supply circuit in the manner stated above through the resistor 161, conductor 180, switch terminal 182, switch contact 60, resilient switch contact arm 64, switch terminal 172, conductor 170 to the neutral conductor of the supply circuit, thus providing 125 volts supply for the resistor 161, thus with the values given above, providing a total of 2,000 watts for the two resistors in the position marked "super" of Fig. 7.

In the next position marked "simmer" the two resistors are connected in series across a pair of supply conductors supplying 125 volts. In the next position marked "high" the resistor 159 alone is connected across 250 volts; in the next or "medium" position the resistor 161 is connected across 125 volts, and in the final or "low" position the resistor 159 alone is supplied with 125 volts. It is also to be noted that in each position excepting the "off" position the circuit through the pilot lamp 136 is closed by the movable contact 96.

It should be noted in connection with this embodiment of my invention that I have provided one position, the "simmer" position which is the lowest heat position, in between the two highest heat positions. This is advantageous when it is desired to heat a relatively large mass quickly up to a certain temperature by use of either of the two higher heat positions, and then maintain it at that temperature by supplying a relatively small quantity of heat thereto for a relatively long period of time, which can be readily accomplished by merely turning the control to the adjacent "simmer" position, conveniently located intermediate the "higher" and "super" positions of the switch.

The operation of the switch in this embodiment of my invention is the same as that described in the previous embodiment. In other words, the arrangement is such that the circuit is always opened or made at the contact 60 and/or 14, before the bridging contact moves from engagement with one set of segmental contacts into engagement with another set. Thus, the circuit is first set up by the bridging contact 54 engaging with the contact segments and then the segment is closed by the arcing contacts 14 and 60. Due to the different arrangement of contact segments in this embodiment of my invention, the contact operating member of this switch will necessarily be formed with a different cam portion for operating the resilient contact arms 64 and 78 than that provided for the switch shown in Figs. 1 to 5. As in the previous embodiment of my invention this same sequence of operations of the switch contacts takes place upon movement of the switch 76 125 volts.

to all of its six positions. In other words the arcing contacts 60 and 74 are first opened upon movement of the switch from one position to another before the bridging contact 54 leaves one set of contact segments to engage with another set. These arcing contacts remain open until the bridging contact 54 is in engagement with the next set of contact segments whereupon one or both of the arcing contacts may be closed depending upon which of the supply conductors are to be connected to the resistors.

In the embodiment of my invention shown in Fig. 8, I have shown a four-position switch capable of providing three different degrees of heat with a pair of resistors 214 and 216 of equal value. Here again, the switch is of the same general type heretofore described, differing only by the arrangement of the contact segments to obtain the desired circuit connections, and accordingly like reference numerals will be used to designate like parts. The particular circuit connections shown in Fig. 8 are as follows: a conductor 192 connects the positive conductor of the supply circuit with a switch terminal 194, which is connected with the resilient switch contact 78. A conductor 202 also connects the positive conductor of the supply circuit with the switch contact 204 cooperable with the resilient switch contact 96 connected by a conductor 206 with the neutral conductor of the supply circuit. Included in the conductor 206 is a pilot lamp 136. A conductor 208 connects the negative conductor of the supply circuit with the switch terminal 210 which is connected with the resilient switch contact 64. The neutral conductor of the supply circuit is also connected by a conductor 196 with the switch terminal 198 electrically connected with the inner contact segment 200. The resistors 214 and 216 are connected by a common conductor 212 to a switch terminal 213, which in turn is connected with the contact segment 218. The other end of the resistor 214 is connected by a conductor 220 with the switch terminal 222 which in turn is connected to the fixed switch contact 14, electrically connected with the contact segment 224. The other end of resistor 216 is connected by a conductor 217 with the fixed switch contact 60. The resistors 214 and 216 in this embodiment of my invention are designed to give their greatest heating effect when connected across a voltage corresponding to that obtained between either the positive or negative conductors of the supply circuit, and the neutral conductor.

Thus in the first or "high" position shown in Fig. 8, the resistors are connected as follows: from the positive conductor of the supply circuit through conductor 192, switch terminal 194, switch resilient contact arm 78, contact 14, switch terminal 222, conductor 220, through resistor 214, conductor 212, terminal 213, switch contact segment 218, bridging contact 54, contact segment 200, switch terminal 198, and conductor 196 to the neutral conductor of the supply circuit. This also connects the adjacent end of resistor 216 to the neutral conductor of the supply circuit, and this resistor is connected to the negative conductor of the supply circuit by the conductor 217, fixed switch contact 60, resilient switch contact arm 64, switch terminal 210, and conductor 208. Thus, for the same voltage values given in connection with the two previously described embodiments in this position the resistors 214 and 216 will be connected in parallel across 125 volts.

In the intermediate or "medium" position shown in Fig. 8, the resistor 216 alone is connected across a pair of supply conductors supplying 125 volts. In the "low" position shown in Fig. 8, the connections established by the switch are such as to connect the two resistors in series with a pair of supply conductors furnishing 125 volts. The switch used in Fig. 8 has a sequential operation of its several contacts the same as the switch described in connection with the other two embodiments of my invention. In other words, the switch contacts are preferably operated in a manner so that the circuit is always made or broken at the arcing contacts 60 and/or 74, so that the bridging contact 54 is moved from one set of segments to another only when the circuit has previously been opened at the arcing contacts.

In the embodiment of my invention shown in Fig. 9, I have illustrated an eight position switch capable of providing six different degrees of heat with two "off" positions. The heating arrangement shown in Fig. 9 utilizes a heating element comprising two resistance elements 228 and 230 of unequal value. The switch employed in this embodiment of my invention is also of the same general type heretofore described, differing only from the switch shown in Figs. 1 to 5 in the number of positions to which the switch may be moved and, of course, in the particular arrangement and number of contact segments to obtain the desired circuit connections. Accordingly, like reference numerals will be used to designate like parts.

In order to avoid complicating the drawings, it will be noted that I have applied reference characters in Fig. 9 as in Figs. 6 to 8, inclusive, only to those circuit connections and parts which are connected to supply conductors in the particular position involved. Thus, no numerals have been applied to the parts and connections in the two "off" positions. Considering the lowermost or "super" position shown in Fig. 9, the circuit proceeds from the negative conductor of the supply circuit through the conductor 236 to the switch terminal 234, resilient contact arm 64, fixed contact 60, and conductor 232 to one end of the resistance heating element 228. The heating elements 228 and 230 are joined at one end by a common terminal, which is connected by a conductor 226 to switch contact 74, resilient contact arm 78, switch terminal 225, and conductor 223 to the positive conductor of the supply circuit. The other end of resistance element 230 is connected by a conductor 238 with the switch contact segment 240, by way of bridging contact 54, contact segment 242 and conductor 244 to the switch terminal 234, and conductor 236 to the negative conductor of the supply circuit. Thus, it can be seen that in this position of the switch both heating elements 230 and 228 are connected in parallel across the positive and negative conductors of this supply circuit, thus supplying, for example, 250 volts to each heating element.

Without going into detail as to the circuit connections in the next or "high" position, it is apparent from the conductors numbered that the heating element 230 alone, is connected across the positive and negative conductors of the supply circuit. Similarly, in the next or "intermediate" position, the resistance element 228 alone is connected across the positive and negative conductors of the supply circuit. The next position is an "off" position of the switch which is

located intermediate the six heating positions of the switch to thereby avoid the necessity of turning the switch a relatively great distance when it is desired to turn the switch "off" from any one of the heating positions thereof. In the "medium" position, the resistance element 230 alone is connected across the positive conductor of the supply circuit and the neutral conductor to thereby obtain a reduced voltage on this resistance element, as compared to the position in which this resistance is connected across the positive and negative conductors of the supply circuit. In the next position or "low" position seen in Fig. 9, the resistance element 228 alone is connected across the neutral and negative conductors of the supply circuit. In the "simmer" position, the two resistance elements 228 and 230 are connected in series across the neutral and negative conductors of the supply circuit. Inasmuch as this circuit involves conductors not heretofore described, it will be traced in detail. As seen in the second position from the top in Fig. 9 of the drawings, the upper end of resistor 230 is connected by the conductor 238, contact segment 240, bridging contact 54, contact segment 246, and conductor 248 to the neutral conductor of the supply circuit. The lower end of resistance 228 is connected by a conductor 232 to the fixed switch contact 60, resilient contact arm 64, switch terminal 234 and conductor 236 to the negative conductor of the supply circuit. As shown, the common terminal of the resistors 228 and 230 is not connected to any supply conductor in this position.

Thus, progressing in a downwardly direction, the respective positions shown in Fig. 9 denote respective circuit arrangements in which the resistor elements 228 and 230 are so connected to the supply conductors as to give progressively greater heating effects, assuming, of course, that the resistor element 230 is of greater value than the resistor element 228. It will also be noted that the first three heating positions of the switch involve connections of the resistor elements either in series or singly between one of the live conductors of the supply circuit and the neutral conductor which, following the previous example, may supply a voltage of 125 volts. Following these three positions is an "off" position, after which the resistors are connected to the two live conductors of the supply circuit, both singly and finally in parallel relation. The voltage obtained between the supply conductors in this embodiment of my invention may be as described heretofore, by way of example, 250 volts between the positive and negative conductors and one-half that value or 125 volts between either the positive or negative conductors and the neutral conductors.

As stated above the switch in the circuit arrangement shown in Fig. 9 operates with a sequential operation of its several contacts in the same manner as the switch described in connection with Figs. 1 to 5. In other words, the switch contacts are operated in a manner so that the circuit is always made or broken at the arcing contacts 60 and/or 74, so that the bridging contact 54 is moved from one set of contact segments to another only when the circuit has previously been opened at the arcing contacts.

From the foregoing it should be obvious that the general type of switch described in connection with Figs. 1 to 5 of the drawings is capable of use in a plurality of different novel circuit arrangements for the connection of plural ele-

ment heating units in different relationships with respect to a supply circuit for obtaining a plurality of different degrees of heat from the resistors.

It should be understood that the value of voltage, resistance and wattage given herein, are merely illustrative and are not intended to be limiting in any sense. Thus, in each of the embodiments shown it is necessary only that a three-wire supply circuit be provided providing different voltages between different pairs of conductors, and in connection with the embodiments of Figs. 7 and 9, that a heating element be provided embodying unbalanced sections. The specific voltage, resistance or wattages are immaterial, since obviously the circuits I have shown can be used in connection with any desired voltage or any desired plural resistor heater assembly.

Having described preferred embodiments of my invention in accordance with the patent statutes, I wish it to be understood that my invention is not to be limited to the particular embodiments disclosed herein since it will be obvious, particularly to persons skilled in the art, that many changes and modifications may be made in these particular structures without departing from the broad spirit and scope of my invention. Therefore, I desire that my invention be interpreted as broadly as possible and that it be limited only by what is set forth in the appended claims.

I claim as my invention:

1. In an electrical system for connection with a three wire supply circuit, a plurality of load devices, movable selector contact means for successively energizing a plurality of spaced selector contacts upon movement of an operating means for said selector contact means in one direction, electrical connections arranged to connect one or more of said load devices in a plurality of different relations with respect to said supply circuit when different ones of said selector contacts are energized at different positions of said movable operating means and including a plurality of arcing switches each having a pair of separable contacts in certain of said connections, with certain of said selector contacts connected, respectively, to one of said supply wires and to one terminal of said load devices, and with one contact of one of said arcing switches connected to another of said supply wires and another selector contact, and the other contact thereof connected to a terminal of said load devices, the other arcing switch having one contact thereof connected to the third supply wire and its other contact connected to a third terminal of said load devices, and common operating means for said movable selector contact means and said arcing switches for energizing said spaced contacts in succession and for opening the contacts of at least one of said arcing switches prior to deenergizing a spaced contact, and for closing the contacts of at least one of said arcing switches only after energizing the next succeeding spaced contact, and operative to close said one arcing switch at least at one operative position of said switch operating means and to open said one arcing switch at least at one other operative position of said switch operating means.

2. In electric heating apparatus having a plurality of supply conductors adapted to be connected to a plurality of conductors leading from a source of electrical energy so that different pairs of said supply conductors are provided with different electromotive forces and a plurality of

resistors; the combination of selector switch means having movable contact means adapted to successively energize a plurality of spaced contacts, means including electrical connections constructed and arranged to establish different circuits between one or more of said pairs of conductors and one or more of said resistors when said spaced contacts are energized, respectively, arcing switch means in each of said different circuits, said connections including direct connections from a pair of said supply conductors to said selector switch means and at least one direct connection between said selector switch means and at least one terminal of said resistors, one of said arcing switch means connected between one of said last mentioned pair of supply conductors and another terminal of said resistors, another arcing switch means connected between the third supply conductor and a third terminal of said resistors and said selector switch means, and common operating means for moving said movable selector contact means to deenergize one of said spaced contacts to energize another and for opening the contacts of at least one of said arcing switches prior to movement of said movable selector contact means to deenergize said one spaced contact, and for closing the contacts of at least one of said arcing switches only after movement of said movable selector contact means to energize said other spaced contact.

3. In electrical apparatus for connection with a three-wire supply circuit, a plurality of load devices, selector switch means including movable contact means for successively energizing a plurality of spaced contacts upon movement of operating means therefor in one direction, electrical connections arranged to connect one or more of said load devices in a plurality of different relations with respect to said supply circuit corresponding to different positions of said operating means including a pair of arcing switches each having a pair of separable contacts in certain of said connections, with certain of said selector contacts connected, respectively, to one of said supply wires and to one terminal of said load devices, and with one contact of one of said arcing switches connected to another of said supply wires and another selector contact, and the other contact thereof connected to a terminal of said load devices and to still another of said spaced contacts, the other arcing switch having one contact thereof connected to the third supply wire and its other contact connected to a third terminal of said load devices and to still another of said spaced contacts, and common operating means for said movable selector contact means and arcing switches for opening the contacts of at least one of said arcing switches prior to deenergization of a spaced contact, and for closing the contacts of at least one of said arcing switches only after energization of the next succeeding spaced contact.

4. In electric heating apparatus, a three wire supply circuit having a neutral conductor, a pair of resistors having a common terminal, selector switch means having movable contact means adapted to be connected to said neutral supply conductor and adapted to successively engage at least two spaced contacts upon movement of operating means therefor in one direction, said spaced contacts connected to said common resistor terminal and one other resistor terminal, respectively, a pair of arcing switches each having a pair of separable contacts, one of said arcing switches connected between another supply

conductor and said one other resistor terminal, the other of said arcing switches being connected between the third supply conductor and third resistor terminal, common operating means for said switches operative in three successive positions thereof to maintain said other arcing switch closed in each position, to close said one arcing switch only at the third position and to maintain said movable contact means engaged with the contact connected with said common resistor 10 terminal at the second and third positions and engaged with the other of said spaced contacts at the first position, so that in successive positions of said movable contact means, said resistors are connected in series with said neutral 15 and another supply conductor, one resistor is shunted across said neutral and another conductor, and both resistors are shunted across said neutral and said other conductors.

5. In electrical apparatus for connection with a three-wire supply circuit, a plurality of load devices, a selector switch means including movable contact means for successively energizing a plurality of spaced contacts upon movement of operating means for said selector switch means 20 in one direction, electrical connections arranged 25

to connect one or more of said load devices in a plurality of different relations with respect to said supply circuit corresponding to different positions of said operating means including a pair 5 of arcing switches each having a pair of separable contacts in certain of said connections, with certain of said selector contacts connected, respectively, to one of said supply wires and to one terminal of said load devices, and with one contact of one of said arcing switches connected to another of said supply wires and another selector contact, and the other contact thereof connected to a terminal of said load devices, and to still another of said spaced contacts, the other arcing switch having one contact thereof connected to the third supply wire and its other contact connected to a third terminal of said load devices, and common operating means for said movable selector contact means and arcing switches for opening the contacts of at least one of said arcing switches prior to deenergization of a spaced contact, and for closing the contacts of at least one of said arcing switches only after energization of the next succeeding spaced contact.

CHARLES H. HODGKINS.
